VARIED TEMPERATURE REFRIGERATOR

Filed May 29, 1930

Fig. 1.

UNITED STATES PATENT OFFICE

FREDERICK A. BERLIN, OF WASHINGTON, DISTRICT OF COLUMBIA, ASSIGNOR TO
AMERICAN CHEMICAL COMPANY, A COMMON-LAW TRUST OF MASSACHUSETTS

VARIED TEMPERATURE REFRIGERATOR

Application filed May 29, 1930. Serial No. 457,363.

This invention relates to refrigerating containers and has for its object the production of a simple and efficient refrigerating container having a common refrigerant containing compartment and a plurality of individually and separately controlled temperature regulated storage compartments.

Another object of this invention is the production of a simple and efficient refrigerating container which may be either constructed for use as a stationary refrigerator suitable for markets, delicatessen stores and the like or may be used upon trucks, wagons, railroad cars, or other forms of movable refrigeration as well as that of the stationary type.

A still further object of this invention is the production of a simple and efficient arrangement of a refrigerant containing compartment and a plurality of storage compartments which communicate with the refrigerant containing compartment and are individually controlled to permit the storage compartments to maintain different degrees of temperature supplied from the main or common refrigerant containing compartment.

Other objects and advantages of the present invention will appear throughout the following specification and claims.

In the drawing:—

Figure 1 is a front elevation partly broken away and partly in section of the refrigerating container.

Figure 2 is a vertical section through the container, and

Figure 3 is a transverse section through one end of the container looking in the direction of the arrow.

By referring to the drawing it will be seen that 1 designates the main body of the refrigerating container which may be formed of any shape or desired structure and is preferably formed or constructed of insulating material in order that the desired temperature may be properly and economically maintained within the interior of the container.

The container is preferably provided with a top cover 2 of any suitable or desired structure which may be hinged at one of its edges as indicated at 3. A suitable grid 4 is supported near the top of the container 1 as

clearly illustrated in Figure 2 and is adapted to support the refrigerant material 5 which preferably may be solid CO_2 or similar substance that sublimates. It should be understood, however, that any form of a cooler may be employed and if it is so desired chemical water ice may be used. The brine system may be used instead of the ice or direct expansion from a refrigerated unit using any of the well known refrigerating agents. It should further be understood that mechanical refrigeration together with brine may serve to produce the refrigeration if it is so desired.

A partition 6 is mounted near the top of the container 1 directly below the grid 4 and below this partition 6 is arranged a plurality of spaced dividing walls 7 for the purpose of producing a plurality of individual storage compartments 8. The front of these storage compartments 8 may be closed by means of suitable doors 9 and within these doors 9 may be placed the usual glass panels 10 of suitable structure in order to permit the contents of the compartments to be viewed when it is so desired.

The partition 6 is provided with a plurality of apertures 11 or openings arranged therein to register with the various storage compartments 8, and suitable valve plates, 80 shutters or louvers 12 are preferably mounted therein in order that these openings 11 may be opened or closed to control the temperature between the refrigerant containing compartment 5 and the storage compartments 8. 85 These valve plates 11 may be operated in any suitable or desired manner by means of the push rod 13 which push rod 13 is connected at its lower end to a suitable thermostat 14 which is illustrated for the purpose or convenience in the nature of a horse shoe expansion thermostat. It should be understood that any suitable or well known thermostat may be employed and also that any suitable or desired valve may be employed for controlling the temperature within the individual compartments 8 from the general or refrigerant containing compartment 5. 95

It is to be understood that within the compartments 8 suitable trays or shelves may 100

be employed as indicated at 15 for the purpose of supporting articles of food.

It should be borne in mind that the present invention has particularly in view the production of an efficient refrigerating medium or container having a refrigerant supported in the upper end thereof in a common compartment and communicating with individual compartments located below or adjacent thereto, the temperature within the individual compartments being controlled through the medium of any suitable or desired valve structure interposed between the refrigerant containing compartment and the storage compartment. It should be further understood that it is the purpose of this invention to provide individual thermostatic controlled means within each storage compartment for controlling the entrance of temperature reducing gases or air from the refrigerant compartment into the storage compartments. This thermostatic control means may be of any suitable or desired structure and instead of using the rod illustrated for a direct movement of the louvers or shutters or valve plates, a hydraulic piston using alcohol or other suitable liquid acting upon the cylinder or electric magnet controlled by suitable wires and contacts may be used without departing from the invention.

In carrying out this invention, it has been found that a refrigerant such as dry ice may be placed within the container 5 at a temperature of -90° , and the various thermostats may be set within the various compartments 8, to maintain a temperature within these various compartments such as follows: -40° for vegetables, 25° for milk, 0° for fish, etc., 18° for butter, 34° for meat.

One of the principal advantages of the present invention is the fact that the present device will permit the food storage or supply house to deliver the various articles of food to the retail merchants, maintaining the various articles at their proper temperatures and by providing the retail merchants with the refrigerating device above described, these various articles of food may be retained at their desired temperatures by the merchants against spoilage. It is a well known fact that the various articles of food requires various degrees of temperature which cannot be obtained by a common storage compartment but by providing the individual temperature controlled storage compartments the food may be placed in those compartments wherein the desired temperature is maintained.

Having described my invention, what is claimed is:

1. A refrigerating container comprising a casing having a refrigerant containing compartment formed therein, a plurality of storage compartments located below said refrigerant containing compartment, valve means

located between said storage compartments and said refrigerant containing compartment, and thermostatic means for opening and closing said valves.

2. A refrigerating container comprising a casing, a refrigerant containing compartment located along the top of said casing, a plurality of storage compartments located below said refrigerant containing compartments, a partition separating the refrigerant containing compartment from the storage compartments and having ventilating openings formed therein, means for opening and closing the ventilating openings, and thermostatic means for controlling said last mentioned means. 70 75 80

3. A refrigerating container comprising a casing, a refrigerant containing compartment located in the top of said casing, a grid mounted therein for supporting the refrigerant carried within the compartment, a partition located below said grid and having a plurality of vent openings formed therein, valves for opening and closing said openings, a plurality of compartments located below said partition, and individually controlled thermostatic means placed in each of said last mentioned compartments for opening and closing said valves whereby different temperatures may be uniformly maintained within the various last mentioned compartments. 85 90 95

4. A refrigerating device of the class described comprising a casing, said casing provided with a refrigerant containing compartment located in the top thereof, a plurality of storage compartments located below said first mentioned compartment, a separate thermostatic means mounted within each of said storage compartments, and valve means interposed between the storage compartments and the refrigerant containing compartment for maintaining a constant and different temperature within each compartment all temperatures being controlled from the refrigerant containing compartment through the medium of said valves and individual thermostatic control means. 105 110 115

In testimony whereof I affix my signature.
FREDERICK A. BERLIN.
